BOILER WATER DRUM MOUNTING

Gulver O. French, Maplewood, N. J., assignor to
 Combustion Engineering-Superheater, Inc., a
 corporation of Delaware

Application July 11, 1945, Serial No. 604,441

3 Claims. (Cl. 122—336)

1

This invention relates to steam generating units having integral furnaces lined with tubes which are cooled by water in circulation with the boiler.

In steam generators of this type and particularly in smaller unitary boilers it is not only desirable to have the furnace and boiler tube structures arranged so that they will have simple flow paths of low resistance between the furnace wall tubes and the boiler but it is also desirable that ample provision be made for the expansion of all tubes and that the relative expansions of all furnace and boiler tubes be fixed with respect to a positive anchorage therebetween. The provision of such an anchorage will eliminate or minimize all undue expansion strains caused by temperature changes due to operating conditions as a result of initial strains due to possible improper erection of the related parts and due to any strains which may otherwise have been imposed by the transport of the assembled unit.

How the foregoing, together with other objects and advantages as may hereinafter appear or are incident to the invention are realized, is illustrated in preferred form in the accompanying drawings which

Figure 1 is a longitudinally sectioned elevational view of a steam generating unit embodying the invention;

Figure 2 is a transverse sectional view on the line 2—2 in Fig. 1;

Figure 3 is an end view on an enlarged scale of the lower boiler drum shown in Fig. 1 illustrating its anchorage to the water wall headers; and

Figure 4 is a fragmentary side view of Fig. 3.

The steam generator illustrated has an upper steam and water drum 10 interconnected with a lower water drum 12 by banks of vertical tubes 13 and 14. Adjacent these tube banks is a furnace 11 having its side walls each lined with a row of water tubes 15 which as shown are connected between headers 16 near the bottom of each wall and a common header 17 at the top of the furnace, although individual upper headers may be provided. Headers 16 are supplied with water by a number of downcomers 18 leading downwardly from the steam and water drum 10. The top header 17 is connected to the steam and water drum 10 by means of riser tubes 19. Hand holes for cleaning out the water walls may be provided as in the outside walls of headers 16 and in the top walls of header 17.

The two lower headers 16 pass beneath and at right angles to lower water drum 12, supporting

2

said drum by means of pads 20 (Fig. 3). The headers 16 rest in turn upon a foundation 21. The downcomers 18 are in alignment with the furnace wall tubes 15 thereby forming continuous side walls from the front of the furnace to the rear of the boiler, to which continuous side walls a relatively simple outer wall structure may be fastened. Optionally additional down comers 18a may be connected to the bottom drum 12 and the headers 16.

Within the furnace is stoker 22 which in this case is of the single retort underfeed type and is shown only in outline. Adjacent to each side of stoker 22 are ash dump grates 23, Fig. 2, which may be alignment with headers 16, whereby the latter serve as clinker chills. Coal is fed to the stoker from hopper 24 by means of a feeding mechanism generally shown at 25.

By the construction described above the headers 16 and drum 12 of the boiler are accurately spaced with respect to one another and the pads 20 from an anchor with respect to which the relative expansions of all tubes may be determined. This spacing is maintained after erection if the steam generator is to be transported as a unit, and the difficulty of accurately spacing and aligning the drums with respect to one another during erection in the field is overcome. The support of the boiler on the headers 16 is also advantageous in transport since this rigidly maintains the relative position of headers 16 with respect to the boiler drum 10 and downcomers 18 will then not be strained during transport.

What I claim is:

1. In a steam generator unit of the bottom-supported type, the combination of a lower water drum extending crosswise of the unit, an upper steam and water drum disposed above said lower drum substantially directly thereover, at least one bank of boiler tubes interconnecting said upper and lower drums and serving to support the upper drum from the lower drum, a furnace combustion chamber adjacent the forward side of said boiler tube bank, water tubes lining the side walls of said furnace chamber and including left and right side wall rows each of which extends at substantially right angles to said transverse lower drum, means connecting the upper ends of said side wall tubes into said upper drum, left and right bottom headers respectively joined with the lower ends of said left and right rows of side wall tubes and respectively extending from forwardly of said transverse lower drum beneath the left and right end portions of that drum to points rearwardly of said drum, means connect-

ing said left and right bottom headers for reception of water from at least one of the aforesaid two drums, bottom-supporting foundation means for said left and right headers adapted to carry the entire weight of those headers plus said side wall tubes and of said lower and upper drums plus said bank of interconnecting boiler tubes and of other pressure parts in the generator, and left and right support members respectively interposed between said left and right lower headers and the said lower water drum for the purpose of supporting said lower drum upon those two headers and also for fixedly spacing that drum above said headers, said support members thus facilitating the proper relative positioning of pressure-part elements of the steam generator during assembly and erection and during operation constituting anchor points with respect to which the aforesaid boiler tubes and side wall tubes connected into circulation with said upper and lower drums expand and contract as the temperature thereof is raised and lowered.

2. In a steam generator unit of the bottom-supported type, the combination of a lower water drum extending crosswise of the unit, an upper steam and water drum disposed above said lower drum substantially directly thereover, at least one bank of boiler tubes interconnecting said upper and lower drums and serving to support the upper drum from the lower drum, a furnace combustion chamber adjacent the forward side of said boiler tube bank, water tubes lining the side walls of said furnace chamber and including left and right side wall rows each of which extends at substantially right angles to said transverse lower drum, means connecting the upper ends of said side wall tubes into said upper drum, left and right bottom headers respectively joined with lower ends of said left and right rows of side wall tubes and respectively extending from forwardly of said transverse lower drum beneath the left and right end portions of that drum to points rearwardly of said drum, left and right sets of downcomer tubes interconnecting said upper steam and water drum with said two bottom headers, bottom-supporting foundation means for said left and right headers adapted to carry the entire weight of those headers plus said side wall and downcomer tubes and of said lower and upper drums plus said bank of interconnecting boiler tubes and of other pressure parts in the generator, and left and right support members respectively interposed between said left and right lower headers and the said lower water drum for the purpose of supporting said lower drum upon those two headers and also for fixedly spacing that drum above said headers, said support members thus facilitating the proper relative positioning of pressure-part elements of the steam generator during assembly and erection and during operation constituting anchor points

with respect to which the aforesaid boiler tubes plus side wall and downcomer tubes connected into circulation with said upper and lower drums expand and contract as the temperature thereof is raised and lowered.

3. In a steam generator unit of the bottom-supported type, the combination of a lower water drum extending crosswise of the unit, an upper steam and water drum disposed above said lower drum substantially directly thereover, at least one bank of boiler tubes interconnecting said upper and lower drums and serving to support the upper drum from the lower drum, a furnace combustion chamber adjacent the forward side of said boiler tube bank, water tubes lining the side walls of said furnace chamber and including left and right side wall rows each of which extends at substantially right angles to said transverse lower drum, a common upper header receiving the top ends of the tubes in said left and right side wall rows and being connected with said steam and water drum, left and right bottom headers respectively joined with the lower ends of said left and right rows of side wall tubes and respectively extending from forwardly of said transverse lower drum beneath the left and right end portions of that drum to points rearwardly of said drum, means connecting said left and right bottom headers for reception of water from at least one of the aforesaid two drums, bottom-supporting foundation means for said left and right headers adapted to carry the entire weight of those lower headers plus said side wall tubes and said upper header and of said lower and upper drums plus said bank of interconnecting boiler tubes and of other pressure parts in the generator, and left and right support members respectively interposed between said left and right lower headers and the said lower water drum for the purpose of supporting said lower drum upon those two headers and also for fixedly spacing that drum above said headers, said support members thus facilitating the proper relative positioning of pressure-part elements of the steam generator during assembly and erection and during operation constituting anchor points with respect to which the aforesaid boiler tubes plus side wall tubes connected into circulation with said upper and lower drums expand and contract as the temperature thereof is raised and lowered.
